CLAIM

The ornamental design for a seat, as shown and described.

DESCRIPTION

This application is related to commonly assigned, co-filed U.S. design patent application Ser. No. 29/776,192, filed on Mar. 29, 2021 by ISSA DE MEDEIROS GAMA et al. entitled “Container”, and commonly assigned, co-filed U.S. design patent application Ser. No. 29/776,193, filed on Mar. 29, 2021 by ISSA DE MEDEIROS GAMA et al. entitled “Container”, which applications are incorporated herein by reference in their entirety.

FIG. 1 is a top, right perspective view of a seat in accordance with the new design;

FIG. 2 is a bottom, left perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top view thereof; and,

FIG. 8 is a bottom view thereof.

The broken lines in the drawings illustrate portions of the seat which form no part of the claimed design.

1 Claim, 8 Drawing Sheets
